UNITED STATES PATENT OFFICE

134,678

DESIGN FOR A BIRD FEEDER

Donald B. Hyde, Newton, Mass.

Application April 2, 1942, Serial No. 106,428

Term of patent 14 years

To all whom it may concern:

Be it known that I, Donald B. Hyde, a citizen of the United States, residing at Newton, in the county of Middlesex and State of Massachusetts, have invented a new, original, and ornamental Design for a Bird Feeder, of which the following is a specification, reference being had to the accompanying drawing, forming part thereof.

In the drawing:

Fig. 1 is a perspective view of a bird feeder

showing my new design looking towards the rear or open end thereof;

Fig. 2 is a front elevation of the bird feeder; and

Fig. 3 is an end view thereof.

I claim:

The ornamental design for a bird feeder, substantially as shown.

DONALD B. HYDE.
